UNITED STATES PATENT OFFICE.

SAMUEL J. HUNTER, OF SAVANNAH, MISSOURI, ASSIGNOR OF THREE-FOURTHS TO WILLIAM SHERMAN HUNTER, JOHN SHERIDAN HUNTER, AND ULYSSES GRANT HUNTER, OF SAME PLACE.

DESIGN FOR A CHURN-DASHER.

SPECIFICATION forming part of Design No. 26,598, dated February 2, 1897.

Application filed December 26, 1896. Serial No. 617,108. Term of patent 14 years.

To all whom it may concern:

Be it known that I, SAMUEL J. HUNTER, a citizen of the United States, residing at Savannah, in the county of Andrew and State 5 of Missouri, have invented a new and original Design for Churn-Dashers, of which the following is a specification.

This invention relates to a new and original design for churn-dashers; and it has for its 10 object to provide a design of this character that shall be both useful and ornamental.

The leading feature of the design resides in a churn-dasher comprising a circular body with opposite flat sides and a circular series 15 of triangularly-shaped blocks arranged at each side of the body and projected laterally from the flat face of such side in a plane concentric with the periphery of the body, each triangular block having its opposite inclined 20 sides converging inwardly toward the center of the body to dispose its apex next to and in radial alinement with the center of the body and its flat base directly adjacent to the periphery of the body.

25 In the drawings, Figure 1 is a perspective view of a churn-dasher embodying the herein-described design. Fig. 2 is a side view thereof. Fig. 3 is an edge view of the dasher.

Referring particularly to the drawings, the numeral 1 designates a circular body having 30 opposite flat sides 2. At each side of the circular body 1 is arranged a circular series of triangularly-shaped blocks 3, projected laterally from the flat face of such side in a plane concentric with the periphery of the body. 35 Each triangular block 3 has its opposite inclined sides 4 converging inwardly toward the center of the body to dispose its apex 5 next to and in radial alinement with the center of the body and its flat base 6 directly 40 adjacent to the periphery of the body. The triangular blocks 3 are alternately arranged, respectively, at opposite sides of the circular body, as clearly illustrated in Fig. 3 of the drawings. 45

What I claim is—

The design for a churn-dasher herein shown and described.

In testimony that I claim the foregoing as my own I have hereto affixed my signature 30 in the presence of two witnesses.

SAMUEL J. HUNTER.
